(57) **CLAIM**

The ornamental design for a cabinet hinge, as shown and described.

DESCRIPTION

FIG. 1 is an environmental perspective view of an embodiment of the inventive design for a cabinet hinge showing the cabinet hinge in an open configuration with associated illustrative screws and with portions of an illustrative connected cabinet and portions of an illustrative connected cabinet door being illustrated in phantom;

FIG. 2 is an elevational view of the right side of the design shown in FIG. 1 with the illustrative associated screws being shown partially in phantom;

FIG. 3 is an elevational view of the left side of the design shown in FIG. 1 with the illustrative associated screws being shown in phantom;

FIG. 4 is a top plan view of the design shown in FIG. 1 with the associated illustrative screws being shown in phantom;

FIG. 5 is a front elevational view of the design shown in FIG. 1 with some of the associated illustrative screws;

FIG. 6 is a back elevational view of the design shown in FIG. 1;

FIG. 7 is an elevational perspective view similar to FIG. 1, but showing the cabinet hinge design in an closed configuration with the illustrative associated screws and with the portions of the illustrative connected cabinet and of the illustrative connected cabinet door being shown in phantom;

FIG. 8 is an elevational view of the right side of the FIG. 7 design;

FIG. 9 is an elevational view of the left side of the FIG. 7 design;

FIG. 10 is a top plan view of the FIG. 7 design with the associated illustrative screws and the portions of the illustrative connected cabinet and of the illustrative connected cabinet door being shown in phantom;

FIG. 11 is a front elevational view of the FIG. 7 design with the associated illustrative screws; and,

FIG. 12 is a back elevational view of the FIG. 7 design. The phantom line showing of environmental structure, including portions of illustrative screws, is for illustrative purposes only and forms no part of the claimed design.
